TEMPERATURE CONTROL FOR CLOTH DRIERS

Frank E. P. Klages, Park Ridge, Ill., assignor to
The Powers Regulator Company, Chicago, Ill.Application November 12, 1932
Serial No. 642,387

7 Claims. (Cl. 236—92)

My invention relates to temperature control devices and particularly to novel means for controlling temperature under abnormal conditions in the operation of cloth driers.

5 Driers of the type to which this invention is applied comprise a large number of steam heated drums or cylinders so arranged that the cloth travels thereover and is dried during its travel. It is customary to provide thermostatic means for regulating the temperature or in other words, the amount of steam supplied to the drums and under normal operation this is sufficient and the results are entirely satisfactory. However, when a stoppage occurs for any of a number of reasons, 10 the emergency frequently results in burning of the cloth. This is due to the fact that the steam pressure builds up immediately due to the fact that there is not the progressive withdrawal of heat by the travel of the wet cloth over the drums. 15 The thermostat will ultimately shut off the steam supply but the action of the thermostats that are best suited for that purpose is comparatively slow and before the steam supply is interrupted, the cloth will be scorched. This has been a serious difficulty which was not overcome until the 20 addition of the improvement herein described. This improvement consists in providing a relay in the fluid supply line to the shut off valve and connecting the relay to the steam space in the drums, the parts being so arranged that as soon as there is an abnormal pressure of steam in the 25 drums, this pressure acting on the relay will admit air under pressure directly to the shut-off valve and close it much earlier than would occur by the 30 thermostat.

In some instances objection is made that the 35 shut-off action even when the described attachment is made is too slow; in other words, that there is a lag both in opening and closing that should be avoided. It will be understood that in 40 normal operation when the cloth has been running with a fairly uniform moisture content, the thermostatic regulator will maintain the steam valve in a position three-fourths to four-fifths closed. The springs in the thermostatic valve are so designed that this is accomplished with the pressure of three and a half pounds assuming a supply pressure of fifteen pounds and will be fully closed at a pressure of six pounds or thereabouts. When 45 using the type of regulator contemplated herein and which is found to be generally satisfactory there is a substantial time lag while the pressure is being built up from three and a half pounds to six pounds at which point the steam valve will be 50 fully closed and during this lag some damage may

be done to the cloth. In the apparatus illustrated as collateral to the principal idea I have illustrated means whereby this lag in closing is eliminated.

The invention will be more readily understood 60 by reference to the accompanying drawings in which:

Fig. 1 is a view, partly diagrammatic, showing the application of my improvement to a conventional cloth drier, and

Fig. 2 is a similar view showing the use of the improvement in connection with mechanism by which a more positive action is secured.

In the drawings I have shown a plurality of rotatable drums 10 mounted in suitable bearings 70 carried on hollow columns 11 to which steam is supplied by means of the pipe 12 and the branches 13. A control valve 14 of well known form is mounted in the pipe 12, and if desired a reducing valve 15 is also furnished. Air under pressure is 75 supplied by means of the pipe 16 and a leak type thermostat 17 is interposed in the air supply pipe, the outlet from the thermostat being by the pipe 18 to the control valve 14. The operating bulb 17a for the thermostat 17 is located 80 adjacent to the surface of a drum, a flexible tube 19 providing connection to the thermostat. The apparatus heretofore described has commonly been installed and my improvement consists in providing a so-called relay valve 20 which 85 may be of conventional form and providing a steam pipe connection 21 thereto from one of the columns 11. A pipe 16a is connected to the pipe 16 from a source of fluid under pressure and an outlet pipe 22 with a restriction valve 23 therein 90 is connected to the pipe 18 that leads to the control valve.

The operation is such that as the steam pressure rises due to any cause such as the stoppage 95 of the machine, the pressure acting through the relay valve will open the connection between the pipe 16a to the pipe 22 and thence to the pipe 18 whereby fluid under pressure is admitted directly from its source to the control valve and immediately close it or positions it so that the steam pressure will not be excessive. This is in anticipation of the closing action of the thermostat 17 which would occur at a considerably later period. The restriction valve 23 100 is provided in order to properly correlate the action of the respective parts and is used when the apparatus is installed in order to secure the desired action.

The details of the thermostat and the relay 110

valve are unimportant so far as the idea here sought to be covered is concerned.

In the apparatus shown in Fig. 2 the elements already described are present and operate as set forth. In addition I provide a positive relay valve 24 having a pipe connection 25 to the main air line, and a pipe connection 26 to the outlet pipe 27 from the thermostatic regulator, this pipe leading through the connection 28 to the steam shut-off valve 14. The outlet connection from the relay valve 24 is a pipe 29 that also connects to the pipe 28 and by a branch 30 to a pilot valve 31 located in the pipe 27. The pipe 27 acts as a continuation of the pipe 32 that extends from the gradual relay valve 33 that is operated by steam pressure admitted through the pipe 34, air being supplied to the relay valve by the pipe 35 connected to the source of air under pressure.

The operation takes place as follows: Whenever pressure builds up in the line 27, 28 due to the closing of the bleeder valve in the thermostatic regulator to say five pounds, at which point the steam valve 14 is about four-fifths closed, this pressure will act on the relay valve 24 to open a direct connection through the pipe 25 with the full air pressure (fifteen pounds or more), and this will be delivered through the pipe 29 to the steam valve. This pressure acting through the pipe 30 on the pilot valve will close the normal outlet from the regulator 17 to the steam valve, so that the air under high pressure will not leak through the regulator and so that when normal conditions are restored, the regulator 17 will operate under its normal conditions and without an excess pressure.

As soon as the thermostat 17a responds to a lower heat condition in the drums, the air pressure controlled by the thermostat 17 will be lowered to a point below five pounds and immediately the relay 24 will close off the direct air pressure connection, the excess pressure in the line 28 being exhausted through the restriction valve 23 or gradual relay 33. Thus the steam valve will be immediately opened to a degree corresponding to the pressure released by the thermostat 17.

In the case of the construction shown in Fig. 2, the relay 33 will act to immediately close the steam valve whenever the steam pressure exceeds a predetermined amount. This will act considerably in advance of the action that would follow the functioning of the thermostat 17 and the relay 24. During normal operation of the apparatus shown in Fig. 2 the control of the steam admission to the drums will be effected by the thermostat 17 and the relay 24, the action of the valve being gradual up to a point at which the valve is approximately four-fifths closed. Any increase in temperature beyond that point will through the action of the relay 24 serve to immediately close the steam valve. A reversal of this action will take place upon a return of normal conditions reflected by the thermostatic element; that is the steam valve will first be opened to a substantial extent and then gradually opened further if the conditions warrant.

While the device has been described for use as a cloth drier it will be understood that the construction and arrangement of parts with slight modifications is adapted for many other uses.

Obviously the form of the drier, the location and arrangement of the thermostat and the location and arrangement of the control appara-

tus by which the steam pressure is utilized are unimportant, and modifications may be made therein without departure from the spirit of my invention.

I claim:

1. Heat control for driers, comprising the combination with a plurality of drier drums and valve means for controlling the feeding of steam thereto, of a thermostat in position to be affected by the temperature of said drums for regulating said valve, and means operated by an abnormal steam pressure for supplementing the action of said thermostat to effect an earlier closing of said valve than would occur under the action of said thermostat.

2. Heat control for driers, comprising the combination with a plurality of drier drums and valve means for controlling the feeding of steam thereto, of a thermostat in position to be affected by the temperature of said drums for regulating said valve, a source of fluid under pressure and a fluid pressure connection between said thermostat and said valve, a relay valve in said connection, and means operated by an abnormal steam pressure in said drums for operating said relay valve to admit fluid under pressure directly from its source to said connection to immediately re-position said valve.

3. Heat control for driers, comprising the combination with a plurality of drier drums and valve means for controlling the feeding of steam thereto, of a thermostat in position to be affected by the temperature of said drums for regulating said valve, a source of fluid under pressure and a fluid pressure connection between said thermostat and said valve, and means operated by the pressure of steam in said drums for admitting fluid under pressure directly to said valve to effect an earlier closing thereof than would occur under the action of said thermostat.

4. In a cloth drier, the combination of a plurality of rotatable drums, means for supplying a heating medium thereto, a fluid-pressure-operated valve, a thermostat for controlling the supply of fluid under pressure to said valve, and means operated by an excess heat condition in said drums for admitting fluid under pressure to said valve independently of said thermostat.

5. Heat control for driers, comprising the combination with a plurality of drier drums and valve means for controlling the feeding of steam thereto, of a thermostat in position to be affected by the temperature of said drums for regulating said valve, means operated by an abnormal steam pressure for supplementing the action of said thermostat to effect an earlier closing of said valve than would occur under the action of said thermostat, and means operating under a pressure built up by said thermostat less than the pressure necessary to close said valve for immediately applying a higher pressure to said valve for positioning the same.

6. In combination, drying means, means for supplying a heating medium thereto, a fluid-pressure-operated valve, a thermostat for controlling the operation of said valve by controlling the supply of fluid under pressure to said valve, and means operating under a pressure in the fluid supply line to said valve less than the pressure necessary to close said valve for opening a connection to a source of fluid under sufficiently high pressure to immediately reposition said valve.

7. In combination, drying means, means for supplying a heating medium thereto, a fluid-pressure-operated valve, a thermostat for controlling
